UNITED STATES PATENT OFFICE

165,335

CIRCULATING HEATER

Paul D. Kilbury, Hawthorne, Calif.

Application March 27, 1950, Serial No. 8,807

Term of patent 14 years

(Cl. D81—19)

To all whom it may concern:

Be it known that I, Paul D. Kilbury, a citizen of the United States, residing at Hawthorne, in the county of Los Angeles and State of California, have invented a new, original, and ornamental Design for a Circulating Heater, of which the following is a specification, reference being had to the accompanying drawing, forming part thereof.

Figure 1 is a front elevation of a circulating heater, showing my design.

Figure 2 is an end elevation of Figure 1 looking at the right end of said figure.

Figure 3 is a rear elevation of Figure 1.

Figure 4 is a plan view of Figure 1.

Figure 5 is an end elevation of Figure 1, looking at the left end of said figure.

I claim:

The ornamental design for a circulating heater, as shown.

PAUL D. KILBURY.
